UNITED STATES PATENT OFFICE.

EDWARD H. KRUSE, OF FORT WAYNE, INDIANA.

SWITCH-BOX SUPPORT.

Application filed October 12, 1923. Serial No. 668,095.

To all whom it may concern:

Be it known that I, EDWARD H. KRUSE, a citizen of the United States of America, and resident of Fort Wayne, in the county of Allen and State of Indiana, have invented certain new and useful Improvements in Switch-Box Supports, of which the following is a specification.

This invention relates to improvements in switch box supports and the object thereof is to afford means applicable in the wall of a building for sustaining switch boxes and the like therein, and which may be applied with the exercise of no more than ordinary skill.

This object is accomplished by the construction illustrated in the accompanying drawings, in which:—

Fig. 1 is a front elevation of a construction embodying the invention;

Fig. 2 is an elevation in a plane at right angles to that of Fig. 1, the supporting bars being shown in section; and

Fig. 3 is a fragmentary perspective view showing the construction of the mounting bars.

The characters appearing in the description refer to parts shown in the drawings and designated thereon by corresponding characters.

The invention comprises a pair of mounts 1, each of which consists of a metallic bar in the form of an even angle in cross section, and which has along the juncture of its two flanges 2 and 3 a series of elongated apertures 4 that are extensive into both of said flanges equally so that each aperture, as it extends into both flanges, affords an opening through each flange out of the plane of the other flange.

The mounts also have in each of their flanges a series of holes 5 through which nails 6 are driven to secure the mounts to the studding 7 of the wall.

In utilizing the invention a pair of mounts are secured to the studding of the wall in spaced relation with each other with their respective flanges 2 lying flat against the studding and with their respective flanges 3 disposed at the remote edges of the corresponding mounts. A switch box 8 having ears 9, of usual construction is positioned between the mounts with its ears 9 extending respectively through the corresponding openings 4 of said mounts and is thereby held fixedly in position supported by said mounts. The apertures 4 in said mounts are spaced so as to accommodate a series of switch boxes arranged in a gang when so desired.

A feature of the invention is that by making the apertures in the angle at the juncture of the two flanges of the mounts, and extensive equally into both flanges, the ears of the switch box may be received through either flange of the mount which admits of the mounts being placed with either of their flanges against the studding as may be most convenient.

What I claim is:—

In an appliance of the class described, a metallic angle bar having a single series of elongated spaced slots and a series of nail holes in each of its flanges, each of said slots extending through the bar at the juncture of its flanges and portions of each of said flanges adjacent thereto.

In testimony whereof I affix my signature.

EDWARD H. KRUSE.
